KENELM JOHN WINSLOW, OF MONTPELIER ROW, TWICKENHAM, ENGLAND.

Letters Patent No. 79,092, dated June 23, 1868.

IMPROVED APPARATUS FOR CONVERTING MOTION.

The Schedule referred to in these Letters Patent and making part of the same.

TO ALL WHOM IT MAY CONCERN:

Be it known that I, KENELM JOHN WINSLOW, of Montpelier Row, Twickenham, in the county of Middlesex, civil engineer, England, have invented an Improved Method of Communicating Rotatory Motion to Axles; and I do hereby declare that the following is a full, clear, and exact description thereof, which will enable others skilled in the art to make and use the same, reference being had to the accompanying drawings, forming part of this specification, in which—

Figure 1 is a front view.

Figure 2 a vertical section of my improved mechanism for rotating axles as applied to a sewing-machine.

Figure 3 is a side view of the drum, drawn on an enlarged scale.

Figure 4 is a front view of the same.

Figure 5 is a side view of the drum, with the outer plate removed to show the internal construction, and Figure 6 is a sectional view of the same.

Figure 7 is a side view of the friction-ring or pulley detached, and

Figure 8 is an edge view of the same.

Similar letters of reference indicate corresponding parts.

My invention of "an improved method of communicating rotatory motion to axles" is applicable to various machines, carriages, and more especially to sewing-machines, which are worked either by steam, pedal, or other power.

In the accompanying drawings I have shown various figures of my improved mechanism as applicable to a sewing-machine.

In carrying out the invention, two flexible connecting-rods, bands, or chains, are made to act upon two hollow drums, inside each of which are suspended one or more pawls. Each pawl works on a cogged, roughened, or ratchet-wheel, fixed on the axle, within the drum, and is kept in position to work by means of a link, attached by a pin to the end of the pawl, the other end of such link being fastened to a ring or pulley, working loose upon the axle or bearings of the drum. Friction is applied to this ring or pulley by means of a weight or spring, so as slightly to retard its free movement. The drums have the same centre of motion as the axle to be turned. When the drum is moved backwards, the link, acting from the ring or pulley before mentioned, on to the pawl, lifts it just free of the ratchet, and keeps it so until the movement is reversed, when it instantly causes it to take or gear into the teeth of the ratchet.

By this apparatus, also, the noise which would otherwise be occasioned by the pawl when trailing on the ratchet is obviated. A cord or band from a pulley placed beside and attached to one of the drums, is passed over pulleys, placed in some convenient part of the machine, to a similar pulley attached to the other drum. The lower portions of the rods, chains, or bands, are fastened respectively to foot-levers or pedals. The machine being put in motion, alternate action is given to the pawls, which, working on the cogged or roughened wheels, impart continuous rotation to the axle.

A is the axle. B B are cogged or ratchet-wheels, fixed on the axle. These cogged wheels are enclosed in hollow drums C C', which work loose on the axle, or in separate bearings. In each of the drums is suspended a pawl, D, which is arranged so as to take into the indentations or teeth of the cogged wheel, as shown in fig. 5. E is a link, attached at one end to the pin F, at the end of the pawl D, the other end of such link being attached to a similar pin, G, which is fixed to the metal ring or pulley H, and which pin G works through a slot in the side of the drum C. The ring or pulley H surrounds the axle, and works on a bearing at the side of the drum, its free movement being slightly retarded by any convenient means, such, for instance, as by the friction-ring K, which is pressed on its outer rim by means of the spring L. When the drum is moved backwards, the link E, being pressed against the friction-ring H, lifts the pawl just free of the ratchet, sufficient play being given to the pin G, in the slot before mentioned, to admit of this. The pawl D is kept free of the ratchet-wheel B until the movement is reversed, when the ring K and link E, acting as a drag, will cause

it instantly to take into the teeth and work upon the ratchet. It will thus be seen that all noise of the pawl trailing on the ratchet is obviated, and its action on the ratchet made instant and effective.

M M are two treadles, to which are attached bands N N. These bands are passed around, and are fastened to the drum C C. The drums are connected by means of the band O, which is passed around and secured to the pulley P, attached to the side of the drum C; thence it is passed over the pulley P' attached to the side of the drum C'. Motion being given to the treadles, an alternate forward motion is given to the drums C and C', and thus the axle A will be made to revolve in one direction, by the means previously described.

Instead of the two drums operated by two treadles, and connected by the cord O over the pulley Q, my improved apparatus may be made to operate nearly if not equally as well, with one drum and treadle, and with an India-rubber or other spring, connected to the side of the drum, at one end, and to any other suitable fixed connection at the other, for retracting the said drum.

Having thus described my invention, I claim as new, and desire to secure by Letters Patent—

1. The combination of the loose hollow drums C, hinged pawls D, link-connections E E G, friction-pulley H, fixed ratchet-wheel B, and shaft A, all constructed and arranged to operate substantially as and for the purpose herein shown and described.

2. In combination with the above, I claim the retarding-rings K and spring L, and also the cord O and pulleys Q, all constructed and arranged to operate in the manner and for the purpose herein shown and described.

In witness whereof, I, the said KENELM JOHN WINSLOW, have hereunto set my hand and seal, the 24th day of March, in the year of our Lord, 1868.

K. J. WINSLOW. [L. S.]
